UNITED STATES PATENT OFFICE

RUTH COLLINS BENDIXEN, OF NEW YORK, N. Y.

DESIGN FOR A CHAIR OR SIMILAR ARTICLE

Application filed May 29, 1929. Serial No. 31,466. Term of patent 3½ years.

To all whom it may concern:

Be it known that I, RUTH COLLINS BENDIXEN, a citizen of the United States, and resident of New York city, in the county of New York and State of New York, have invented a new, original and ornamental Design for chair or Similar Article, of which the following is a specification.

The figure is a perspective view showing a chair or similar article embodying my new design.

The ornamentation shown is continued throughout the back, sides, legs and supports of the chair or similar article.

I claim:

The ornamental design for a chair or similar article, as shown and described.

Signed at New York city, in the county of New York and State of New York, this 21st day of May A. D. 1929.

RUTH COLLINS BENDIXEN.
